UNITED STATES PATENT OFFICE.

CHARLES M. MANLY, OF BROOKLYN, NEW YORK.

VARIABLE-CAPACITY PUMP.

1,212,791.

Specification of Letters Patent. Patented Jan. 16, 1917.

Application filed February 4, 1911. Serial No. 606,618.

To all whom it may concern:

Be it known that I, CHARLES M. MANLY, a citizen of the United States, residing at 113 Montague street, Brooklyn, in the county of Kings and State of New York, have invented a new and useful Variable-Capacity Pump, of which the following is a specification.

My invention relates to variable capacity multiple cylinder pumps, and more particularly to means for varying the capacity thereof and controlling the interaction of the cylinders.

One object of this invention is to provide a multiple cylinder pump in which the fluid circuits of the multiple cylinders are separate from, but capable of interconnecting with, each other.

Another object is to provide means for varying the capacity of the cylinders of said pump, and another object is to provide means for utilizing power for operating the capacity varying means.

With these and other objects in view, my invention consists in the novel combination, construction and arrangement of parts hereinafter described and more particularly pointed out in the claims.

In my prior Patents Nos. 710485 and 801097, I have shown multiple cylinder pumps with means for varying the capacity of the said cylinders, but in these constructions the multiple cylinders have all been interconnected to a common fluid circuit.

In certain practical applications of these pumps and especially where they have been employed for generating fluid pressure for operating two or more fluid pressure motors I have found that it would be advantageous

to connect up the several cylinders of such a pump to form two or more separate fluid pressure circuits, and also to provide means for interconnecting and disconnecting the said fluid pressure circuits to and from each

other. Such a pump resembles in some respects the combination of several separate and distinct pumps, but a single pump comprising multiple cylinders so connected as to form multiple fluid pressure circuits may

be provided with a single mechanism for varying the capacity of all of the cylinders, thus insuring that an exactly equal change in the capacity of each cylinder will occur simultaneously with any change in the capacity of any cylinder. While, therefore, I prefer to use, and have illustrated, a pump-

ing mechanism in which a single mechanism is used for varying the capacity of the multiple cylinders thereof, and thereby the amount of fluid circulated through the multiple circuits into which the said cylinders are grouped, I do not limit my invention to such a construction, as several variable capacity pumps may be so arranged that their mechanisms for varying their capacity are caused to act in synchronism, without departing from the spirit or scope of my invention.

In the accompanying drawings, which illustrate one form in which my invention may be carried out, Figure 1 is longitudinal sectional elevation of the pump; Fig. 2 is a cross section on the line 2—2 Fig. 1; Fig. 3 is a cross section on the line 3—3 Fig. 1; Fig. 4 is an end elevation looking in the direction of the arrow 4 in Fig. 1; Fig. 5 is a partial end elevation looking in the direction of the arrow 5 in Fig. 1; Fig. 6 is a partial top plan view of the left hand end of Fig. 1; Fig. 7 is a developed view of the valves and their housing which are used to control the mechanism for varying the capacity of the pump cylinders; Figs. 8, 9 and 10 are an elevation partly in section, a top plan view and a cross section on the line 10—10 of Fig. 8, of the valve mechanism for controlling the interconnection to and separation from, each other of the multiple circuits of the pump, and Fig. 11 is a diagrammatic plan view showing the pump adapted to operate two independent hydraulic motors. Fig. 12 is a detail view of the valve head on an enlarged scale.

Referring now to the drawings in which the same reference characters relate to the same or corresponding parts in all the figures, the numeral 20 indicates a crank chamber from which radiate six cylinders 21, 22, 23, 24, 25 and 26 respectively. Radiating from the crank chamber 20 are also six valve chambers 27, 28, 29, 30, 31 and 32 respectively, each of the said valve chambers being in line with one of the said cylinders. Formed in the valve chamber 27 are three recesses or ports 33, 34 and 35 respectively, the middle one 34 being connected to the cylinder 21 by the passage 36. In the valve chamber 28 are three similar ports 37, 38 and 39, the port 38 being connected by a similar passage, not shown, to the cylinder 22. Likewise the valve chamber 29 has three ports, 40, 41 and 42, the port 41 being

connected by a similar passage, not shown, to the cylinder 23. In the valve chamber 30 are the three ports 43, 44 and 45, the port 44 being connected by the passage 46 to the cylinder 24. The valve chamber 31 has the three similar ports 47, 48 and 49, the port 48 of which is connected by a similar passage, not shown, to the cylinder 25, while the valve chamber 32 has the three similar ports 490, 50 and 51, the port 50 being connected by a similar passage, not shown, to the cylinder 26. Slidably mounted in the valve chamber 27 is the piston valve 52 comprising the 3 heads, 53, 54 and 55, the head 54 being of a width substantially equal to the width of the port 34. Slidably mounted in the other valve chambers 28, 29, 30, 31, and 32 are similar valves 56, 57, 58, 59 and 60 respectively, the middle head of each being substantially equal to the width of the middle port of its respective valve chamber. Formed in the right hand face of the valve chamber 27, Fig. 1, is a passage 61 which connects at its inner end to the port 33, while a similar passage 62 connects at its inner end to the port 35. Similarly the valve chamber 30 is provided with the passages 63 and 64, which connect with the ports 43 and 45 respectively. Each of the other valve chambers is provided with similar passages which connect with their respective outer and inner ports. The outer ports 33, 40 and 47 of the valve chambers 27, 29 and 31 respectively are thus connected by their respective passages to the manifold 65 secured to the valve chambers by the screws 66. Similarly the manifold 67 connects together the outer ports 37, 43 and 490 of the valve chambers 28, 30 and 32 respectively, while the manifold 68 connects together the inner ports 35, 42 and 49 of the valve chambers 27, 29 and 31 respectively, and the manifold 69 connects together the inner ports 39, 45 and 51 of the valve chambers 28, 30 and 32 respectively.

Formed integral with the manifold 65 is a pipe 70, shown broken in Figs. 1 and 4, and the purpose of which will be later explained. Similarly the manifolds 67, 68 and 69 have formed integral with them the respective pipes 71, 72 and 73. Each of the valves 52, 56, 57, 58, 59 and 60 is provided with a gudgeon pin 75 connecting thereto a connecting rod 74 which terminates at its inner end in a shoe 76 by means of which it is given a rocking connection through the ring 77 and the retaining rings 78 and 79, with the valve crank pin 80 on which the said rings are journaled. The valve crank pin 80 is formed integral with but eccentric to the sleeve 81 journaled in the bearing 82 mounted in the crank chamber 20, the eccentricity of the crank pin 80 being such that in Fig. 1 the center thereof is below the plane of the paper, while the line passing

through the center of the said crank pin and the center of the sleeve 81 is perpendicular to the plane of the paper.

Rotatably mounted in the sleeve 81 is a crank shaft 83 embodying a crank pin 84, 70 the left hand side of the said crank shaft 83 passing through and being journaled in the sleeve 85, which in turn is journaled in the bearing 86 mounted in the crank chamber 20. Mounted on the crank pin 84 is an eccentric bushing 87 with a split bushing 88 (formed in two halves) interposed therebetween, the eccentricity of the bore of the said eccentric bushing 87 with respect to its outer peripheral surface being equal to the eccentricity of the crank pin 84 with respect to the crank shaft 83. The eccentric bushing 87 terminates at its left hand end in a spur gear 89 which meshes with the internal gear 90 in which the sleeve 85 terminates at 80 its right hand end, the difference in diameters of the two said gears being equal to twice the eccentricity of the crank pin 84 with respect to the shaft 83, so that any turning of the sleeve 85, with respect to the shaft 83 causes a simultaneous turning of the eccentric bushing 87 with respect to the crank pin 84. It is readily seen that with the parts in the positions shown in Figs. 1 and 2, the outer peripheral surface of the 90 eccentric bushing 87 is eccentric with respect to the shaft 83 an amount equal to twice the eccentricity of the crank pin 84 with respect to the shaft 83, while if the eccentric bushing be rotated 180 degrees with respect to the crank pin 84, from its position there shown, the two eccentricities will counteract each other, thus causing the outer peripheral surface of the said eccentric bushing 87 to be concentric with the crank shaft 83. Rotatably mounted on the eccentric bushing 87 is a ring 91 against which abut the shoes 92 in which the connecting rods 93 terminate. The connecting rods, shoes 92 each cover slightly less than one sixth the peripheral 110 surface of the ring 91, being free to slide circumferentially thereon, and being prevented from lifting therefrom by the retaining rings 94 under which they are free to slide. The upper end of each connecting 115 rod has a rocking connection through the pin 95 with a piston 96 slidably mounted in each of the cylinders 21 to 26 respectively. Any rotation of the shaft 83 carrying with it the eccentric bushing 87, causes the said 120 pistons to be reciprocated in their respective cylinders, except when the eccentric bushing 87 is in the position with respect to the crank pin 84, where its eccentricity exactly neutralizes the eccentricity of the 125 said crank pin. In the position shown in the drawings the two eccentricities are in line with each other and add their effect together and the pistons 96 have their maximum stroke. In effecting the variation in 130

the capacity of the cylinders by varying the length of the stroke of the pistons as above described, it is necessary that the valve crank 80 shall always be at right angles to the real crank arm of the piston crank. The real crank arm is a line drawn from the center of the shaft 83 to the center of the outer peripheral surface of the eccentric bushing 87, and the direction of this line changes at 5 an angular rate, only one half as great as the angular rate at which the eccentric bushing is turned on the crank pin 84, it is necessary that the eccentric bushing 87 be connected to the sleeve 81 which drives the 10 valve crank pin 80 by some mechanism that rotates the valve crank pin in unison with the shaft when the eccentric bushing is not being adjusted, and when the bushing is adjusted will advance the valve crank pin in 15 synchronism with the real crank arm of the composite crank pin composed of the crank pin 84 and the bushing 87.

The mechanism shown consists of a double eccentric piece 97 fitted into the right hand end of the eccentric bushing 87 and prevented from turning with respect thereto by the pin 98, the said double eccentric comprising one eccentric 99 concentric with the bushing 87 and a second eccentric 100 concentric with the shaft 83 when the parts are in the positions shown, the two eccentrics being therefore eccentric to each other an amount double the eccentricity of the crank pin 84 with respect to the shaft 83. 20 Rotatably mounted on the eccentric 99 is a square shoe 101 which fits in and is free to slide in a vertical slot in the left hand face of the plate 103, while the eccentric 100 has rotatably mounted on it a square shoe 102 which fits in, and is free to slide in, a horizontal slot in the right hand face of the said plate 103, the two slots in the said plate being thus at right angles to each other and each of a depth equal to one half the thickness of the said plate. The said plate 103 is secured by the rivets 105 to the flange 104 in which the sleeve 81 terminates, the slot in the right hand face of the plate 103 being in line with the line passing through 25 the center of the shaft 83 and the center of the valve crank pin 80.

In operation, when the bushing is adjusted, the one eccentric 99 is sufficient to properly adjust the valve crank pin in synchronism with the real crank arm of the composite crank pin. The eccentric 99 is in effect merely a pin at the center of the outer periphery of the eccentric bushing, working in a slot in the disk of the sleeve 81 of the 30 valve crank pin, radial to the axis of rotation. It is obvious that the slot, which bears a fixed relation to the crank arm of the valve crank pin must always coincide with the line connecting the supposed pin at the 35 center of the eccentric bushing and the axis

of rotation, which line as explained above is the real crank arm of the composite crank pin of the pump pistons. When the crank pin 84 and the eccentric bushing are rotating as a unit this connection acts as a simple 70 shaft coupling and rotates the sleeve 81 carrying the valve crank pin in unison with the driving shaft, for the sleeve 81 and the driving shaft are in axial alinement and consequently the eccentrics 99 and 100 have 75 no radial movement in their slots. The purpose of having two eccentrics is to provide a driving connection when the eccentric bushing is at its zero position. In this position the eccentric bushing is concentric 80 with the axis of rotation and consequently would merely turn in its slot without driving the sleeve 81. By employing two eccentrics oppositely disposed, one or the other is always eccentric to the center of rotation to 85 have an effective driving engagement with the disk on the sleeve 81. The sleeve 81 is kept in its proper longitudinal position with respect to the double eccentric 97 by the lip 106 on the ring 107 held in the bore 90 of the sleeve 81 by the pin 108, the said lip 106 projecting into the groove 109 in the said shaft 83.

Mounted on the left hand end of the crank chamber 20 and secured thereto by the 95 screws 111 is a casing 112 from the left hand end of which projects the main driving shaft 113 which is journaled in the bushing 114. Formed intermediate the ends of the shaft 113 is a collar 117 between one side 100 of which and the end of the bushing 114 is a thrust bearing 115, and between the other side of which and the shoulder 116 of the casing is a thrust bearing 119. Formed in the right hand portion of the shaft 113 are 105 screw threads 120, while the crank shaft 83 is prolonged to telescope into the bore of the said shaft 113 to which it is fastened by the key 121.

Mounted on the threads 120 is a coating 110 nut 122 and surrounding the nut 122 is a sleeve 123 in which are formed longitudinal slots 124 in which are slidably mounted the blocks 125. Slidably mounted on the sleeve 123 is a ring 126 provided with a collar 127 between one side of which and the half yoke 128 is a thrust bearing 129, and between the other side of which and the other half yoke 130 is a thrust bearing 131. Connecting the ring 126, blocks 125 and nut 122 120 are pins 132. The right hand end of the slotted sleeve 123 is connected by the pins 133 to the sleeve 85, and the two half yokes 128 and 130 are connected to each other by the screws 134. If now the yokes be forced 125 to the right, such movement will cause the nut 122 and the sleeve 123, through the blocks 125, to turn in a clockwise direction with respect to the shaft 113, when viewed from the left hand end of Fig. 1, thus turn- 130

ing the eccentric bushing 87 with respect to the crank pin 84 in the same direction and through an angle proportional to the extent to which the said yokes are pushed to the right. Since the yokes exert their pushing effect on the said nut through the thrust bearings 129 and 131, the said yokes may be relatively fixed as regards rotation of the shaft 113 and still exert their pushing effect 5 on the nut 122, and thereby adjust the eccentric bushing while it is rotating with the crank shaft 83. The length of the screw 120 and of the slots 124 may be made such that with the proper pitch to the screw threads, 10 the eccentric bushing 87 will be rotated 360 degrees on the crank pin 84 by pushing the nut 122 to the extreme limit of its motion to the right in Fig. 1. Since 180 degrees movement of the eccentric bushing 87 on the 15 crank pin 84, from the position shown, causes the outer peripheral surface of the said eccentric bushing to be concentric with the shaft 83 and thereby reduces the stroke of the pistons to zero, the remaining 180 degrees of possible movement of the said eccentric bushing will carry its center back to the point from which it started or back to maximum stroke. However, while the double eccentric 97 and its coacting parts previously described keep the valve crank pin 80 always at right angles to, or 90 degrees ahead or behind, the real crank arm of the eccentric bushing during the first 180 degrees of movement of the said bushing, yet 20 at the mathematical point of zero stroke there is no length to the real crank arm and consequently at this mathematical point the angle between it and the valve crank pin disappears. As soon as the eccentric bushing 25 is rotated the minutest amount more than 180 degrees, so as to carry the eccentric bushing out of zero stroke, the angle between the real crank arm and the valve crank pin reappears and is immediately 90 degrees, but if the valve crank pin was 90 degrees behind the real crank arm during the first 180 degrees of movement of the eccentric bushing, it will be 90 degrees ahead during the second 180 degrees. The result 30 of this is, that if, when the crank shaft 83 was rotated, the valves 52, 56, 57, 58, 59 and 60 moved outwardly in their respective valve chambers while their corresponding pistons in the cylinders 21, 22, 23, 24, 25 and 26 moved inwardly, when the eccentric bushing was in any position of its first 180 degrees of adjustment, the said valves will move inwardly when the pistons move inwardly during all positions of adjustment of the eccentric bushing in its second 180 degrees of 35 adjustment. In the first case the pistons 96 will therefore suck in fluid during their inward strokes, from the inner ports of their respective valve chambers, and during their outward strokes will force it out to the outer

ports of the said valve chambers, while in the second case, they will suck in fluid from the outer ports and force it out to the inner ports, thus causing the direction of flow of the fluid to be reversed.

The force necessary to push the yokes 128 and 130 and thereby adjust the stroke of the pump becomes of considerable account in machines of commercial size, and I therefore utilize power derived from the pump itself to move the said yokes by a fluid pressure adjusting mechanism broadly similar to that shown in my Letters Patent 801096, but here shown in an improved form which I will now describe.

Formed integrally with the casing 112, and parallel to and in the same horizontal plane with the main shaft 113, are two adjusting cylinders 136 Fig. 6 in each of which is mounted a piston 137 suitably fastened to its rod 138, the said rods passing snugly through suitable bores in the inner ends of said cylinders and being prolonged to pass through the ears 139 formed on each side of the yokes 128 and 130, the yokes being secured to the said rods between the collars 140 and 141 suitably fastened to the said rods. Closing the outer end of each cylinder is a plug 142 and connected to the space in the cylinders between the pistons 137 and the plugs 142 are two pipes 143, while connected to the space in the said cylinders between the pistons and the inner ends thereof are the two pipes 144. If fluid under pressure is passed through the pipes 143 into the outer ends of the cylinders 136 it will there act against the ends of the pistons 137 thereby forcing the yokes 128 and 130 to the right and thereby adjusting the length of stroke of the crank of the pump. If fluid under pressure is passed through the pipes 144 into the inner ends of the cylinders, it will act against the pistons 137 forcing them to the left, unless they are already at the limit of their motion in this direction, and thereby adjust the stroke of the said crank in the opposite direction. In order to obtain the fluid pressure for operating the adjusting pistons described, I connect one end of the pipe 145 to one side of one of the main fluid circuits, as through the valve chamber 30, Fig. 1, and the other end of the said pipe I connect to the control valve block 146 mounted in the shell 147 on top of the casing 112, while a similar pipe 148 is similarly connected through the valve chamber 30 to the other side of the same main fluid circuit and to the said valve block 146. The pipes 143 and 144 connected to the adjusting cylinders 136 are also connected to the valve block 146, and by suitable valves and passages in the said valve block 146 which I will later describe, I control the fluid pressure, tapped from the main fluid circuits of the pump by the pipes 145 and 146.

148, for operating the adjusting pistons, and thereby I utilize power for performing the work of adjusting the stroke of the pump.

Connected to one of the collars 141 (Fig. 6) by the pin 149, is a link 150, the other end of the said link being connected by the pin 151 to the lever 152. The said lever extends crosswise in the casing 112 and is connected at its other end by the pin 153 to the link 154, which is connected by the pin 155 to the rod 156 which is slidably mounted in the said casing 112. Connected to the left hand end of the rod 156, outside of the said casing, by the pin 157 is a link 158 which is also connected by the pin 159 to the lever 160 fulcrumed on the pin 161 in the bracket 162 extending from the casing 112. The internal or floating lever 152 has a rocking connection through the pin 163 with the rod 164 slidably mounted in the bore 165 formed in the upper part of the casing 112, as more clearly seen in Fig. 1. The slide rod 164 has formed across its left hand end a T slot 166 which coacts with the groove 167 formed near the right hand end of the valve 168 slidably mounted in the bore 169 of the valve block 146, whereby any longitudinal motion of the said slide rod 164 will be communicated to the said valve 168, but any side thrust coming on the lever 152 will be taken up by the slide rod 164 and thus be prevented from causing the valve 168, which must be an accurate fit in its bore, to wear itself or its bore. The lever, links and rods, together with the valve and valve block just described coact to control the use of fluid pressure in operating the adjusting pistons 137 which operate the stroke adjusting mechanism heretofore described. As the said valve block with its valves and passages is rather complicated, I have shown in Fig. 7 a developed view of it and its valves, to more clearly explain the interaction of the various parts.

Referring now to Fig. 7, the valve 168 shown mounted in the bore 169 of the valve block 146, comprises the five heads, 170, 171, 172, 173 and 174 respectively, while the bore 169 has formed in it the seven ports 175, 176, 177, 178, 179, 180 and 181 respectively. By means of the two pipes 144 (Fig. 6) the port 176 (Fig. 7) is connected to the inner end of both of the adjusting cylinders 136, while the port 178 is similarly connected by means of the pipes 143 to the outer end of both of the said cylinders 136. By means, which I will later describe, a supply of fluid pressure is constantly maintained in the port 177. With such fluid pressure in the said port 177, any longitudinal motion of the adjusting valve 168, from the position shown, where the heads 171, and 172 respectively cover the ports 176 and 178, causes fluid pressure to be admitted to one or the other of the said ports from which it passes either

through the pipes 144 or the pipes 143 into one end or the other of the adjusting cylinders 136 where it acts against the pistons 137 and forces the yokes 128 and 130 to move and thereby adjust the pump crank 70 stroke as heretofore described.

The fluid pressure constantly maintained in the port 177 above described is mainly obtained from the main fluid pressure circuits of the pump, by the means which I will now describe. The pipes 145 and 148 leading from the outer and inner ports respectively of the valve chamber 30, belonging to one of the sets or groups interconnected by the manifolds 67 and 69, are connected to the top of the valve block 146 as already described. Formed in the valve block 146 just below the pipes 145 and 148 is a bore 189 which is closed at its outer end by the plug 190. Mounted in the left hand end of the plug 190 is a puppet valve 191, while a second puppet valve 192 is mounted in the bore 194 in the said valve block in line with and just to the left of the valve 191 and a compression spring 193 is interposed between the heads of the two said valves. Connecting the bore 194 to the pipe 148 is a passage 195 and connecting the bore 189 to the pipe 145 is a similar passage 196. Fluid pressure in the pipe 148 is therefore free to pass therefrom, through the passage 195 and, by lifting the valve 192, into the passage 197 formed between the passages 195 and 196. Similarly fluid pressure from the pipe 145 is free to pass through the passage 196, and, by lifting the valve 191 into the said passage 197. Formed in the valve block 146, below the plane of the paper in Fig. 7 is a passage 198, shown dotted, one end of said passage 198 being connected to the passage 197, while the other end is connected to the right hand end of the bore 199 formed parallel to and just above the adjusting valve bore 169 previously described. Slidably mounted in the bore 199 is the valve 200, which, for reasons later explained, I term the pump valve, and which comprises the two heads 201 and 202 joined by the stem 203. Projecting from the left hand head 202 is a stem 204 and surrounding the stem 204 is a compression spring 205, one end of which abuts against the head 202, and the other end against the cover plate 206, which closes the enlarged bore 207 in which the said spring is mounted. Formed in the bore 199 is a counterbored port 208 which is connected by means of the passage 209 with the port 177 previously described. Any fluid pressure passing into the passage 197 from either the pipe 145 or the pipe 148 is free to pass through the passage 198 into the end of the bore 199, where acting on the end of the valve 200 it will tend to force said valve to the left. If the said fluid pressure is sufficient to

overcome the pressure of the spring 205 it will force the valve stem 204 to the left till it abuts against the cover plate 206, in which position the valve head 201 will have moved 5 to the left of the port 208, thus permitting the fluid pressure in the right hand end of the bore 199 to pass therefrom through the passage 209 into the port 177. In a similar manner the two pipes 210 and 211, Figs. 1 10 and 7, connected to the ports 33 and 35 respectively of the upper main valve chamber 27, which belongs to the other group of cylinders, lead fluid therefrom to the valve block 146, and if it is desired to be able 15 to use fluid pressure from this group of cylinders for performing the adjustment of the pump stroke, it may be done by providing the said pipes with passages and check valves opening into the passage 197, 20 similar to those just described for the pipes 145 and 148, or the pipes 210 and 211 may be provided with shunt pipes 212 and 213 respectively and check valves 214 and 215 respectively connecting through the pipe 216 25 with the said passage 197 as shown in Fig. 7. Thus pressure generated in either side of the circuit of either group of cylinders is conducted to the port 177, where under the control of the adjusting valve 168, it may be 30 utilized for operating the adjusting pistons as already described. It is readily seen that the fluid pressure in the port 177 will come from whichever pipe has the highest pressure, and that the check valves will cut off 35 communication with the other pipes. At the same time that fluid under pressure is admitted from the port 177 through the port 176 to the inner ends of the adjusting cylinders 136, an equal amount of fluid is forced 40 out of the outer ends of the said cylinders, due to the motion of the pistons 137, and such fluid passes through the port 178 and into the port 179 from whence, as later described, it is led back into the low pressure 45 or suction sides of the main fluid circuits of the pump. Similarly fluid pressure admitted from the port 177 through the port 178 and into the outer ends of the adjusting cylinders 136 causes an equal amount to 50 be forced out of the inner ends of said cylinders through the port 176 and into the port 175 from which it is similarly led into the low pressure sides of the main fluid circuits. 55 The fluid exhausted from the adjusting cylinders 136 into the port 176, when the adjusting valve 168 is moved to the left and high pressure is admitted to the opposite ends of the said adjusting cylinders through 60 the port 178, is free to pass from said port 176 into the port 175, thence through the passage 217, and into the passage 218 where it is free to divide, and part of it pass through the passage 219, and by lifting the 65 check valve 220, into the passage 196 and

from thence through the pipe 145 into the main fluid circuit, if the side of the fluid circuit to which the passage 196 is connected is at the time the low pressure side. If the passage 196 is at the time under high pressure, all of the fluid exhausted into the passage 218 will pass into the bore 221 from whence it will pass through the hole 222 into the passage 223, shown dotted, and thence by the hole 224 into the passage 225. From 70 the passage 225 the exhausted fluid is free to divide and part of it pass through the radial holes 226 in the plug 227 in the bore 228 and into the axial bore 229 in the said plug, where by lifting the check valve 230 it 75 may pass into the passage 195 if the said passage is at the time connected to the low pressure side of the main fluid circuit of one group of cylinders. The other part of the exhausted fluid in the passage 225 is free to 80 pass therefrom through the radial holes 231 in the bushing 232 in the bore 233, and into the axial bore 234 in the said bushing, where it is free to lift either the check valve 235 and pass into the passage 236 and from 85 thence through the pipe 211 into the side of the fluid circuit to which the said pipe is connected, or it will lift the check valve 237 and pass into the larger bore 238 in the bushing 232 and pass from thence through 90 radial holes 239 and into the passage 240 and from thence through the pipe 210 into the side of the circuit to which the said pipe is connected. 95

As explained and shown in my U. S. Letters Patent No. 801097 and in my pending application above referred to, I provide means for collecting and returning to the main fluid circuits of the pump any fluid leaking therefrom. This is especially advantageous where the pump is utilized as the fluid pressure generator of a hydraulic variable speed gear, where the fluid acted on by the pump is circulated in a closed fluid circuit from the pump to one or more 100 motors, and back to the pump and the return to this circuit of fluid leakage as rapidly as it occurs is necessary in order to keep the circuit completely full of fluid, as the maintenance of a full circuit is essential to the proper operation of the hydraulic gear. In such use of the pump the fluid is preferably oil, which serves the double function of transmitting the power and lubricating the working parts and the fluid which 110 leaks from the circuits to the interior of the crank chamber there mingle with the reserve supply into which the rotating parts 115 splash and thus are kept lubricated. In the present case the fluid leaking by the pistons 120 and valves collects in the crank chamber 20 Fig. 1 from whence it is free to pass through the holes 241 in the bearing bushings 82 and 86 and into the casing 112. Closing the bottom of the said casing is a pan 242 attached 125 130

thereto by the screws 243, the said pan being divided into two compartments, 245 and 246 respectively, by the vertical wall 244, the compartment 245 being covered by a wire net strainer attached to the frame 247 secured by the screws 248, whereby all the fluid passing into the compartment 245 will be strained of any solid particles.

Mounted in the casing 112 and secured to the bosses 600 by the screws 249 is a gear pump 250, which for convenience, I term a leakage pump. The said leakage pump embodies a pinion 251 secured to the shaft 252 on the right hand end of which is formed a gear 253 which meshes with the gear 254 formed on the left hand end of the slotted sleeve 123 heretofore described. Meshing with the pinion 251 is a second pinion 255 secured to the shaft 256, the right hand end of the said gear pump thus formed being closed by the cover 257 in which the said shafts 252 and 256 are journaled. Assuming the shaft 113 to be driven by some external source of power in a clockwise direction as viewed in Fig. 5, the gear 253 will be driven counter clockwise thereby, and the leakage pump 250 will tend to suck in fluid through a suitable passage, provided in the boss 258 on the right hand side thereof and force it out through a similar passage in the boss 259 on the left hand side. Connected to the boss 258 is a pipe 260 to which is connected a pipe 261 leading into the side of the compartment 245 in the pan 242. The pipe 260 is continued beyond its junction with the pipe 261 to the housing 147 on top of the casing 112, the said pipe 260 being there connected through the side of the valve block 146 (Fig. 7) with the enlarged bore 263 in which the bore 221 previously described terminates. Connected to the boss 259 on the pressure side of the leakage pump 250 is a pipe 264, the other end of which is connected through the housing 147 with the valve block 146, the said connection being made through the side of the said valve block by a passage 265 which terminates in the central longitudinal passage 266 in the valve block 146 as clearly shown in Fig. 7. The right hand end of the passage 266 is connected by the passage 267 with the bore 268 which it crosses, the passage 267 terminating in the bore 199 previously described.

Mounted in the bore 268 is a puppet valve 269 on the left hand end of which is formed a stem 270. Surrounding the stem 270 and abutting against the said puppet valve 269 and a plug 271 in the enlarged bore 272 is a spring 273 which keeps the said valve pressed against its seat with a predetermined force. Connecting the enlarged bore 272 to the passage 223, shown dotted in Fig. 7, to which the bore 221 is also connected as already described, is a passage

274, while a second passage 275 connects the said bore 272 also with the port 179, the said passage 275 crossing the bore 199 through the counterbored port 276. Formed in the stem 203 of the pump valve 200 is a hole 277 which extends through the stem 204 thereof and connects the enlarged bore 207 with the bore 199 between the heads 201 and 202. Slidably mounted in the bore 221 already described is a valve 278, which for convenience I term a low pressure relief valve, and which comprises a head 279 from the right hand end of which projects a three pointed guide stem 280, while projecting from the left hand end of the said head 279 is a stem 281 on which is formed a collar 282. Mounted between the said collar 282 and the right hand end of the enlarged hole 263 is a compression spring 283, while a similar spring 284 is mounted between the other side of the said collar and the cover plate 206, the said springs tending to keep the said valve 278 in the position shown with the bore 221 closed from communication with the enlarged bore 263. Connected to the bore 221 near the valve head 279 is a passage which is shown dotted in Fig. 7 and as terminating at its lower end in the port 180, while connected to the passage 266 is a passage also shown dotted and as terminating in the port 181, the passage 266 being thus connected to the bore 221 when neither the valve head 173 nor the head 174 covers the port 180 or 181 respectively, the said passages, ports and valve heads thus constituting a switch, which may be opened or closed by movement of the valve 168.

In some applications of my improved pump the fluid pressure generated by it is utilized as already stated for operating fluid pressure motors and the fluid exhausted by the said motors is returned to the suction side of the pump at the same rate, except for leakage, as the motors receive the fluid under pressure from the pump, the fluid thus circulating in a closed circuit from the high pressure side of the circuit of one group of pump cylinders to a motor and back to the low pressure or suction side of the circuit of the same group of cylinders, and where the pump is used for such purposes I find it advantageous to maintain a back pressure substantially higher than atmospheric pressure on the low pressure or suction side of the circuit of each group of cylinders, the leakage pump in such cases serving a double purpose. Since the leakage pump 250 runs whenever the main driving shaft 113 is revolved, the said leakage pump sucks up the reserve fluid and the leakage collected in the compartment 245 of the pan 242 and forces it through the pipe 264 and the passage 265 into the passage 266 from which it is free to pass through the interconnect-

ing ports and passages into the passages 219 and 225 and from thence, through the check valves and pipes already described, into whichever sides of the two main circuits are the low pressure or suction sides of the pump. If the pressure of the leakage pump rise above the amount necessary to force the head 279 of the low pressure relief valve 278 out of the bore 221 against the action of the spring 284, the excess fluid will pass into the enlarged bore 263 and from thence will be discharged through the pipe 260 (Fig. 5) back to the suction side of the leakage pump 250, and such fluid so discharged in passing by the point where the pipe 261 joins the pipe 260 will have an injector effect tending to draw other fluid up from the pan 242 to the suction side of the said leakage pump, and thereby reducing the force necessary to drive said leakage pump 250. Of course fluid will blow off through the pipe 260 only when the leakage pump supplies more fluid to the main circuits than is leaking therefrom, but as I find it advantageous in certain applications of this mechanism to make the capacity of the leakage pump great enough to always give an oversupply, a reserve supply of fluid is in such cases kept in the pan 242 and the low pressure relief valve is blowing off practically all of the time that the machine is in operation. On this account it is advantageous as regards the efficiency of the machine to arrange the discharge in this manner to reduce the power necessary to run the leakage pump. Also, the having of the discharge connected to the suction side of the leakage pump instead of permitting it to blow off into the casing 112 as heretofore, prevents the said discharge from becoming mixed with air and drawn back later into the leakage pump in such mixed condition, as in certain applications of the machine the fluid operated on is oil, and the operation of the machine is much better the freer the oil in its circuits is of air.

I have explained above how the port 177 is automatically supplied with high pressure fluid from the main circuits when there is high pressure in either side of the said circuits, and how such high pressure fluid is used for operating the mechanism by which the stroke of the pump is adjusted. It is readily seen, however, that when the said stroke is zero, there is no pumping action and therefore there is no high pressure in either side of either circuit. In order to supply fluid pressure for adjusting the crank stroke out of zero, I provide a reservoir 286 (Fig. 7) and connect the pipe 216, previously described, to the bottom thereof. Slidably mounted in the said reservoir 286 is a free piston 287. By means of the valved fitting 288 on top of the said reservoir air is admitted to the upper part of

the said reservoir when the piston is at the bottom thereof. In some uses air under pressure is forced into the upper part of the said reservoir by a hand pump or any suitable means. With the said reservoir thus connected to the pipe 216, any fluid pressure in the port 197 or the pipe 216, coming thereto from the main fluid circuits as already explained, acts on the bottom of the piston 287 forcing it upward and compressing the air on the upper side, so that when the crank stroke is brought to zero, there is stored in the said reservoir a volume of fluid under pressure, which being connected to the port 197 and thereby to the port 177 of the adjusting valve, provides fluid pressure for operating the adjusting mechanism to carry the crank stroke out of zero. Owing to the difficulty of preventing air from leaking past a piston, I find it advantageous to cover the upper side of the piston 287 with a layer of thick oil 300, or other more viscous fluid, so that the air is prevented from coming into direct contact with the said piston and leaking by it and mixing with the oil in the lower part of the reservoir which flows to and from the main circuits.

As the pressure in the main circuits sometimes fluctuates rapidly, there is at such times a tendency for the fluid pressure to surge back and forth in the pipe 216, with the result that the check valves 191, 192, 214 and 215, already described, tend to hammer on their seats and thereby not only pound themselves to pieces, but also make an objectionable noise. In order to overcome this, I provide the said check valve 191 with a small plunger or stem 290 which is slidably mounted in a bore 291 in the plug 190 and so fitted thereto that while fluid can flow slowly past the said plunger into or out of the said bore, yet it prevents the said plunger from being rapidly reciprocated and therefore prevents the said check valve 191 from hammering on its seat. Similarly I provide the check valve 192 with a plunger fitted to a corresponding bore in the valve block 146. In some applications of my pump I find that a plunger on one end of the check valves does not give sufficient dashpot effect to prevent hammering of the said valves and I have therefore shown the check valve 214 by which the pipe 210 is connected to the pipe 216, as provided with plungers 301 and 302 at each end coöperating with suitable bores 303 and 304 in the valve shell and cap thereof respectively, and I find that this prevents the hammering in all cases. The check valve 215 is similarly provided with plungers at either end coöperating with suitable bores.

As it is a very difficult matter to get the crank out of zero stroke unless there is fluid pressure available in the port 177 of the

adjusting valve for operating the adjusting mechanism, and as it sometimes happens that the pressure stored in the reservoir 286, as above described, leaks out or is used up, 5 I provide means for enabling the leakage pump 250 to be called on at such times to supply sufficiently high fluid pressure to operate the said adjusting mechanism. The spring 205 which tends to force the pump 10 valve 200 to the right till the end thereof is against the end of the bore 199 in which it is mounted, is made of such a stiffness that the fluid pressure on the right hand end of it is necessary to force the head 201 to the left of 15 the port 208 is sufficiently high to operate the crank stroke adjusting mechanism. If the fluid pressure introduced into the right hand end of the valve bore 199 from the passage 197 is therefore not sufficiently high 20 to operate the said adjusting mechanism it will be unable to force the pump valve 200 sufficiently to the left to enable it to pass into the port 177. As the valve head 201 is made of a width just equal to the width of the 25 port 208, it is apparent that if the right hand end of the bore 199 is disconnected from the port 177, then the said valve head is either just covering the port 208 or the port 177 is connected to the middle portion 30 of the bore 199 and consequently to the passage 266. In either case if the operator attempted to perform an adjustment of the crank stroke he would find that his movement of the adjusting valve 168 as previously 35 described could not cause an adjustment to be performed. If, however, he moves the said adjusting valve in either one direction or the other until either the head 173 or the head 174 thereof covered the port 180 or 40 the port 181, such closing of either of said ports will cut off communication between the passage 266 and the valve bore 221. The leakage pump will therefore be caused to raise its pressure until it is sufficiently high 45 to raise the valve 269 in the bore 268 and thus permit the fluid that blows off by the said valve 269 to pass through the passage 274 and the bore 221 into the passage 218. The spring 273 is made sufficiently stiff to 50 require that before it can be raised the leakage pump must raise its pressure sufficiently high to operate the adjusting mechanism, and such high pressure from the said leakage pump on passing into the bore 199 passes 55 therefrom through the passage 209 into the port 177 where it is available for such use. If the head 201 of the pump valve 200 happens to cover the port 208, the high pressure from the leakage pump on passing into 60 the bore 199, also passes through the hole 277 in the said valve and acting on the left hand end thereof forces the said valve to the right, thus permitting the said high pressure fluid to pass into the port 177. This over- 65 comes any sluggishness or hesitation on the

part of the valve 200 when it accidentally rests in a balanced condition covering the port 208. It is thus seen that the leakage pump may be called on to furnish high pressure fluid for operating the crank stroke adjusting mechanism at any time that there is not sufficient pressure obtainable from the main circuits for such purpose. 70

As the variation in the length of stroke of the crank for each degree of angular motion of the eccentric bushing on the crank pin is greater the nearer the length of stroke is to zero, and as the length of stroke is exactly zero only when the center of the eccentric bushing is exactly coincident with 75 the center of the crank shaft, it is sometimes difficult for the operator to so adjust the control mechanism as to cause the crank stroke to be brought to zero exactly, even minute movements of the control rod 156 80 causing the length of stroke of the crank to vary appreciably. In order to enable the operator to easily adjust the stroke to zero and to readily know when it is zero, I provide the control rod 156, as shown in Fig. 6, 85 with a groove or notch 400 which coacts with the pawl or button 401 pressed against the rod by the spring 402, the pawl 401 being slidably mounted in the bore 403 formed eccentrically in the plug 404 which is 90 threaded into the eccentric bore 405 in the plug 406 which is in turn threaded into the casing 112. If there is no lost motion in the various joints of the floating lever 152, the yokes 128 and 130, nut 122, thread 120, 95 and other coacting parts by means of which the crank stroke is adjusted and controlled, so that the crank stroke is exactly the same for definite positions of the control rod 156 no matter whether the rod 156 is being ad- 100 justed backward or forward, then the groove 400 is made to exactly fit the rounded or otherwise shaped end of the pawl 401, and the said groove is so positioned in the rod 156 that when the pawl is in the groove the 105 crank stroke is exactly zero. It is then both easy for the operator to adjust the stroke to zero and to know when he has effected such adjustment, since the pawl tends to assist the control rod to move after it has started 110 to enter the groove but resists movements of the rod when it is fully into the groove. However, I find it very difficult in practice to avoid a considerable amount of lost motion in the various joints above referred to, 115 and consequently the position of the control rod 156 is quite different for zero stroke when coming from one side of zero than when coming from the other side. I therefore usually make the groove 400 in the control rod of a width equal to the pawl plus twice the lost motion in either direction. The pawl therefore does not act against the side of the groove to resist movement 120 of the rod in either direction until the rod 125 130

has moved the extra amount necessary to make up for the lost motion in the joints. As it is difficult in manufacturing practice to locate the groove and pawl so exactly that they will properly locate the exact zero of stroke, I provide the eccentrically bored plugs 404 and 406 above described, and it is readily seen that by turning these two plugs the center of the pawl can be shifted to one 10 side or the other as desired, and that by turning the plugs in the opposite directions the pawl will be shifted longitudinally without raising or lowering its center. It is furthermore seen that by having these plugs 15 threaded, as shown, the force of the spring 402 may be increased or decreased as desired.

As the areas of the passages connecting the control valve to the adjusting cylinders 20 are in some uses of the device restricted to prevent the fluid from passing through them too quickly, thereby limiting the rapidity with which the operator may adjust the stroke of the pump, and as in such 25 cases, the operator is likely to exert so much force on his control rod as to bend or injure the connection between the floating lever 152 and the control valve 168, I provide the two lugs 407 and 408 formed in the casing 30 112 in the plane of the lever 152 and so position these lugs that while they permit the lever 152 to be moved sufficiently to operate the valve 168, yet they act as stops to prevent the valve from being moved too far 35 and also being in the plane of the lever, any undue stress on it will be taken up on them and thus prevent any injury to the valve and its connecting parts. It is furthermore seen that if the crank stroke is at zero and 40 the leakage pump or its coacting valves should fail to supply fluid pressure to the adjusting mechanism to move the crank stroke out of zero, the operator may move his control rod till the floating lever abuts 45 against one of these lugs 407 and 408 and then by manual exertion on the control rod force the nut 122 to one side or the other and thus adjust the stroke out of zero.

I have above stated that the middle head 50 of the main valves of the pump are made of a width substantially equal to the width of the middle port of their respective valve chambers. In Figs. 1 and 3, I have shown the main valve 52 as provided with a middle 55 valve head in the edges of which are formed V notches 306 and 307, and in practice I make the distance from the points of the V notches 306 in one edge to the points of the V notches 307 in the opposite edge slightly 60 greater than the width of the port 34, and similarly I provide V notches in the middle head of each of the other main valves arranged in a similar manner. The object of the V notches is to cause the valves to give

a more gradual opening and closing of the 65 middle port, for since the valve crank is either ninety degrees ahead or ninety degrees behind the pump crank, the valves are moving at their highest velocity just as they are opening or closing the middle port of the 70 valve chamber and the piston at this same instant is moving slowest since it is at either its outer or its inner dead center, and if at its inner dead center it is instantaneously 75 changing from a condition of sucking fluid into its cylinder to a condition of forcing it out. If the valve abruptly change the middle port connection from where it is letting low pressure fluid be sucked into the cylinder, to where the cylinder is connected to 80 the high pressure side of the main fluid circuit, before the piston has moved far enough on its outward stroke to really begin to force fluid from its cylinder, the high pressure fluid in the main circuit rushes into the said cylinder, suddenly compressing the slightly elastic fluid therein and causing a hammering noise which is especially noticeable when the pump is operating at high pressure and high speed. The abruptness of the opening 85 of the valve where there are no V notches, or their equivalents, is readily seen when it is noted that with the valve stroke and piston stroke as here shown, the valve opens 90 about twenty times as fast as the piston moves when the piston crank is at full stroke and is moving through the first three degrees of its travel from either dead center, whereas the total movement of the valve is 95 only about one half as great as the total movement of the piston. As the stroke of the piston crank is decreased, the opening 100 of the valve becomes relatively more and more abrupt, and since with a constant amount of power absorbed by the pump, the 105 pressure of the fluid will be increased exactly as the crank stroke is decreased, the difference between the pressure of the fluid in the cylinder when the piston is sucking in and when it is forcing fluid out becomes 110 greater and this difference makes the abruptness of opening of the valve worse and worse. By providing the head of the valves 115 with V notches and properly proportioning them as to number, length, breadth and depth I have been able to make pumps work without appreciable noise at speeds of over twelve hundred revolutions per minute and pressures of over two thousand pounds. I have also found it advantageous, where the 120 middle port is utilized to control the flow of fluid and where the valve coöperating therewith is consequently provided with a middle or controlling head, to make the width of the valve head between the V notches in its 125 opposite edges slightly wider than the port, so that the piston will have actually begun to compress the fluid in the cylinder before

the valve opens, thereby tending to make the pressure in the cylinder nearer equal to that in the high pressure circuit when the valve connects it to the cylinder. Where the outer 5 and inner ports are utilized to control the flow of fluid, the valve has no middle head, but the other heads are made longer and the V notches are then made in the inner edges of each head, and the distance between the 10 points of the V notches is made slightly less than the distance from the inner edge of one port to the inner edge of the other. I also find it advantageous to so space the V notches in each edge of the valve that the 15 edge becomes a series of sharp points, so that there is at no period of the stroke of the valve any abrupt change in the space between the valve edge and the edge of the port through which the fluid is flowing, 20 thereby obviating any abrupt changes in the velocity of flow of the fluid. It is readily seen that by properly proportioning the V notches the area of port opening for the passage of the fluid to and from the cylinder 25 can be made to change in any desired relation to the change in velocity of the piston in its stroke, and I find in practice that good results are obtained where the V notches are so proportioned that the area of port opening 30 varies in substantially the same manner as the velocity of the piston, the velocity of flow of the fluid through the port opening thus varying in synchronism with the velocity imparted to the fluid by the piston 35 movement, or as the sine of the angle of the crank.

Referring again now to Figs. 1 and 4 where the pipes 70, 72 and 71, 73 leading from the manifolds 65, 68 and 67, 69 respectively by which the cylinders are arranged in two groups of three each, are shown broken; where it is desired to provide means for interconnecting the two groups of cylinders either at the will of the 40 operator or automatically by some coacting mechanism, before leading the said pipes to the mechanisms to which the fluid pressure is to be delivered, I interpose in the said 45 circuits the control valve shown in Figs. 8, 50 9 and 10. This control valve comprises a main shell 350 in which are formed the two symmetrically arranged chambers 351 and 352, in which are rotatably mounted the valve bodies 353 and 354 respectively. 55 Formed in the chamber 351 at the lower level are the three equidistant ports 355, 356 and 357. At the same level in the chamber 352 are the three ports 358, 359 and 360, the port 356 of the chamber 351 being connected to the port 359 of the chamber 352 by the passage 361. Connected to the port 355 is the pipe 72, here shown broken, but intended to represent the same pipe 72 shown in Fig. 4 as connected to the mani-

fold 68. Similarly the port 358 is connected to the pipe 73 leading from the manifold 69. Connected to the ports 357 and 360 are pipes 362 and 363 respectively. Formed in the chamber 351 diametrically opposite the port 357 and of an equal width and height is a blind port 364, while diametrically opposite the port 356 is a similar blind port 365. In the chamber 352 are similar blind ports 366 and 367. At a higher level in the chambers 351 and 352 there are similar sets of ports 368, 369, 370, 371, 372 and 373, 374, 375, 376, 377 shown dotted in Fig. 9 and some of them in section in Figs. 8 and 10, the ports 369 and 374 being connected by the passage 378, while connected to the ports 368 and 373 are the pipes 70 and 71 respectively leading from the manifolds 65 and 67 respectively of Fig. 4. Connected to the ports 370 and 375 are the pipes 379 and 380. The valve body 353 comprises a top 381 on which is formed a gear 382, while depending from the lower face of the said top 381 are the four lobes 383, 384, 385 and 386, the outer peripheral surfaces of which fit snugly against the inner surface 90 of the chamber 351, the said lobes being joined together at the bottom of the said chamber by a plate 387 which also fits the bore of the said chamber. Formed integrally with the said lobes is a mid plate 95 388 which also fits the bore of the chamber 351 and thus divides it into an upper and a lower compartment. All of the ports in the chamber 351 are made of an equal size and the four said lobes are made of a width 100 equal to that of the ports, while the lobe 383 is arranged diametrically opposite to the lobe 385, and the lobe 384 is diametrically opposite the lobe 386. The valve body 354 in the chamber 352 comprises a top plate 390, gear 391, four lobes, 392, 393, 394 and 395, a bottom 105 plate 396 and a mid plate 397, similar in all respects to the corresponding parts of the valve body 353. Formed on the valve body 353 is a stem 398 on which is mounted a 110 crank handle 399 by means of which the valve body 353, and through the intermeshing gears 382 and 391, the valve body 354, may be rotated.

With the parts in the positions shown in 115 Figs. 8, 9 and 10 any fluid brought into the upper or lower compartment of either chamber of the valve shell, by the pipes 70, 71, 72 or 73 respectively finds a free passage 120 through its respective compartment to the pipes 379, 380, 362 or 363 respectively, but the lobes which cover the passages 361 and 378 prevent communication between the fluid in the two chambers, while the mid plates 125 prevent communication between the upper and lower compartments of their respective chambers. The diametrically opposite arrangement of the lobes and ports as above

described makes the valve bodies balanced against the pressure of the fluid passing through them.

In Fig. 11 of the drawing the pump is shown as adapted to operate two independent hydraulic motors 450 and 451. The motors, which may be of any desired type, are provided with outer ports for receiving the fluid under pressure and inner ports through which the fluid is returned to the pump. As shown, the pipe 379 delivers fluid under pressure from the upper compartment of the chamber 351 of the control valve 350 to the outer port of the motor 450 and the pipe 362 returns the fluid from the inner port of the motor to the lower compartment of the chamber 351. Similarly, the pipe 380 delivers fluid under pressure from the upper compartment of the chamber 352 of the control valve 350 to the outer port of the motor 451 and the pipe 363 returns the fluid from the inner port of the motor to the lower compartment of the chamber 352.

The operation of the mechanism is as follows:—The shaft 113 being driven by some external power in a clockwise direction when viewed from the left hand end of Fig. 1, the pipe 362 is connected to a source of fluid supply and leads fluid therefrom through the lower compartment of the chamber 351 of the circuit control valve 350 and from thence by the pipe 72 to the manifold 68 connected to the inner ports of the valve chambers 27, 29 and 31, while the pipe 379 delivers fluid pressure from the upper compartment of the said chamber of the control valve 350 to some receptacle or mechanism requiring fluid pressure to be delivered to it, such fluid pressure being brought into said control valve from the outer ports of the valve chambers 27, 29 and 31 through the manifold 65 and pipe 70. Similarly the pipe 363 from the lower compartment of the chamber 352 of the control valve 350 leads fluid, from the same or a second source of supply, through the pipe 73 and the manifold 69 to the inner ports of the valve chambers 28, 30 and 32, while the pipe 380 leads fluid under pressure from the upper compartment of the said control valve chamber to a second receptacle or mechanism, said fluid pressure being delivered to said upper compartment from the outer ports of said valve chambers 28, 30 and 32 by the manifold 67 and pipe 71. Since all the pistons have a common crank pin that actuates them, they all must at all times have equal strokes, and if all of the cylinders are of the same diameter all must furnish equal amounts of fluid under pressure to the manifold to which their respective valve chambers are connected and must all receive equal amounts of fluid from the other manifold belonging to the same

group. If for any reason a higher fluid pressure is desired or obtained in the pressure side of the manifold of one group than in the pressure side of the manifold of the other group, such difference in pressure in the two groups will in no way affect the operation of the pump. If for any reason it is desired to deliver more fluid to one receptacle or driven mechanism than to the other, the operator can, by moving the control valve handle 399, swing either the lobe 385 around to partly close the port 357 or the lobe 394 to partly close the port 360, in either case as the lobe closes the delivery port in one chamber of the control valve, the lobes 384 and 393 will simultaneously open up the ports 356 and 359 an equal amount, thus permitting the fluid that is throttled off in one chamber to pass over to the other chamber and from thence through its delivery pipe into the receptacle or mechanism connected thereto. If the control handle 399 be moved 30 degrees in either direction it will completely shut off the delivery port of one or the other of the control valve chambers and cause all the fluid from this chamber to be delivered to the other chamber along with an equal amount already delivered to and through this latter chamber. By means of the blind ports, above described, in the valve chambers, the lobes 95 which are in front of the said blind ports are caused to have the same variation in radial pressure as the diametrically opposite lobes which coat with the delivery and bypass ports, and consequently the control valve remains perfectly balanced in all positions. Similarly if the direction of flow of the fluid in the control valve is reversed by carrying the pump stroke through zero, the lobes of the control valve coacting with 100 the ports in the upper compartments of the chambers of said control valve cause a similar diverting of the fluid pressure delivery from one chamber to the other by similar movements of the control valve handle. At 110 the same time that the fluid pressure delivery is diverted by movement of the control handle, the fluid supply through the control valve is similarly affected since the same amount of throttling occurs simultaneously in both compartments of either chamber of the control valve.

When the pump is connected to two separate motors in the manner shown in Fig. 11, the control valve 350 may be operated to produce any desired relative speeds of the two motors or to stop either motor independently of the other. When the control handle 399 is in the position shown in Figs. 9 and 11, with the pump circuits disconnected the motors 450 and 451 will receive equal volumes of fluid under pressure from the pump and, if the motors are identical, will be driven at

the same speed. Now if the handle 399 be rotated through a small angle in a clockwise direction as shown in Fig. 9, the lobe 394 will partially cover the ports 360 and 375 and the lobes 384 and 393 will uncover to the same extent the passages 361 and 378 between the valve chambers. With the parts in this position a portion of the fluid delivered by the cylinders 22, 24 and 26 will be cut off from the motor 451 and delivered with the fluid from the cylinders 21, 23 and 25 to the motor 450 thereby reducing the speed of the motor 451. If the crank 399 be moved sufficiently for the lobe 394 to entirely cover the ports 360 and 375 all the fluid delivered by both sets of cylinders will pass through the motor 450 thereby doubling the speed of that motor while the motor 451 will remain idle. If the handle be moved in the opposite direction the motor 450 will have its speed reduced or be stopped according to the extent to which the handle is moved.

In order to decrease the length of stroke of the pump and thereby decrease the volume of fluid delivered by each group of cylinders, the operator pushes the upper end of the lever 160 to the right in Fig. 6, thereby pulling the control rod 156 to the left, and the pin 149 on the adjusting yoke 130 acting as a temporary fulcrum for the floating lever 152 causes the adjusting valve 168 to move to the left with the said lever 152, thereby causing the head 172 (Fig. 7) to uncover the port 178. Fluid pressure in the port 177, brought thereto from the pressure sides of the main circuits or from the storage reservoir 286 as heretofore described, passes from the port 178 to the outer end of the adjusting cylinders 136, forcing the pistons 137 and thereby the yokes 128 and 130 to the right in Fig. 1, and thereby causing the pump stroke to be decreased. As soon as the yokes 128 and 130 begin to move to the right under the action of the fluid pressure brought into the adjusting cylinders 136, the upper end of the floating lever 152 in Fig. 6, is carried thereby to the right, and with the control rod 156 acting as a temporary fulcrum, the lever 152 pulls the adjusting valve 168 to the right until the valve head 172 again covers the port 178 thus shutting off the fluid from the adjusting cylinders 136, and with fluid on both sides of the pistons 137 the said yokes are locked in position by the valve 168 when the head 172 covers the port 178, since the head 171 will simultaneously cover the port 176 to which the other end of the said adjusting cylinders are connected. Similarly to increase the stroke of the main pistons, the operator moves the upper end of the control lever 160 to the left, thereby causing the head 171 of the control valve 168 to uncover

the port 176, admitting fluid pressure thereto from the port 177, and thence to the inner ends of the adjusting cylinders 136 to move the pistons 137 to the left and thereby increase the stroke of the main pistons, until the valve 168 has been thereby moved to the left to the same extent that the operator has moved it to the right, and the head 171 again covers the port 176.

Starting with the parts in the positions shown in the drawings, where the main pistons have their full stroke and the adjusting pistons are at their extreme position of outward adjustment, as the operator moves the upper end of the control lever 160 to the right in Fig. 6 the adjusting yokes 128 and 130 will simultaneously move to the right, decreasing the stroke of the main pistons, until the center of the eccentric bushing 87 is concentric, or nearly so, with the crank shaft 83. If now there happen to be pressure in the storage reservoir 286, any further movement of the control lever 160 in the same direction will open the port 178 to the fluid pressure and admit it to the outer end of the cylinders 136 as before and will cause the yokes to move still farther to the right, thereby carrying the center of the eccentric bushing through zero to a position where it is again eccentric to the center of the shaft 83, but in passing through zero the center of the eccentric bushing shifts its angular position with respect to the valve crank 80 by exactly 180 degrees, thereby causing the inner and outer ports of the main valve chambers to change their functions, the ones which were low pressure becoming high pressure, and the ones that were high pressure becoming low pressure as heretofore described. The direction of flow of the fluid through the circuit control valve 350 is thereby reversed when the crank stroke is carried through zero, and the reversal of flow in said valve occurs simultaneously in both its chambers.

If when the crank stroke was brought practically to zero, as just described, there was no fluid pressure stored in the reservoir 286, the yokes 128 and 130 would cease following the movement of the control lever when the crank stroke became practically zero until the said lever had been moved far enough ahead of them to cause the adjusting valve 168 to be sufficiently displaced to cause the head 173 to close the port 180, when immediately the leakage pump would be cut off from direct connection to the low pressure side of the circuit and the said leakage pump would raise its pressure which would pass into the port 177 as previously described, and finding the port 178 open would pass therethrough into the adjusting cylinders 136 and perform the adjustment of the stroke, carrying it through zero

to the other side where the stroke would cause the main circuits to again furnish pressure to the port 177 for operating the adjusting pistons. If at any time there is insufficient pressure in the storage reservoir and in the main circuits for operating the adjusting pistons, the leakage pump will automatically come into play and furnish the fluid pressure for operating the adjusting pistons. On the other hand the provision of the storage reservoir prevents having to call on the leakage pump to furnish adjusting pressure except on very few occasions, thereby relieving the said leakage pump of the greatly increased tendency to wear occasioned by its pumping at high pressure. It is also readily seen that the provision of a storage reservoir for use in operating the adjusting mechanism at zero stroke also prevents lost motion of the control lever at zero stroke, since without the reservoir the fluid pressure for adjusting the stroke through zero is not obtained until the control valve 168 is moved far enough from its neutral position to cause the head 173 or 174 to close the port 180 or 181 respectively, and in some applications such a lost motion of the control lever at zero stroke is quite objectionable. It is to be understood that I do not limit myself to the grouping of the cylinders into two sets of 3 each, for it is obvious that the pump may have any number of cylinders and that by suitable manifolds they may be connected into any number of groups of any number of cylinders each either the same or different numbers in each group, and that the cylinders may also all be of the same maximum capacity or each may be different from the other. So far as I know, no one prior to my invention conceived, or employed, a pump having multiple cylinders connected into multiple groups and I shall therefore claim the same broadly. And such a pump provided with means for varying the capacity of the cylinders is also believed by me to be broadly new, also a multiple cylinder, multiple circuit pump with means for interconnecting or disconnecting the circuits is believed by me to be broadly new. Furthermore the employment in combination with a variable capacity pump of a reservoir for automatically storing fluid under pressure for operating the capacity varying means is believed by me to be broadly new as well as such a combination with the addition of a secondary pump for also furnishing fluid pressure for operating the capacity varying means, and I shall claim both combinations broadly.

I am also not aware of the prior employment of the combination of a main fluid pressure pump, a secondary or leakage returning pump and means for causing the excess of fluid returned by the leakage pump

to be returned in a closed circuit to the suction side of the said leakage pump and I shall claim the same broadly. From much experience in the practical construction and operation of pumps working at high speeds and high pressures, I find the successful operation of such pumps to be largely dependent on the details of construction and I have therefore embodied in this application for Letters Patent many details which I have invented and which are believed by me to constitute distinct advances in the art and I shall therefore claim these details specifically.

Throughout the specification and claims of this application, I have described my invention as a "pump," but it is obvious that the mechanism disclosed may be used as a hydraulic motor by connecting either the inner or the outer manifolds with a suitable source of fluid pressure, and I therefore wish it to be distinctly understood that I have used the word "pump" merely to indicate the general character of the apparatus, and that my invention is in no wise limited to the use of the apparatus as a pump.

I claim as my invention:—

1. In a pump, the combination with multiple cylinders grouped into multiple sets to supply fluid pressure to separate multiple circuits, of means for interconnecting and disconnecting the said multiple circuits, substantially as described.

2. In a pump, the combination with multiple fluid pressure generating elements, of passages connecting the fluid pressure to separable multiple circuits, and means for interconnecting and disconnecting the said passages, substantially as described.

3. In a pump, the combination with multiple fluid pressure generating elements, of means for varying the volume of fluid pressure generated per cycle of operation of the said pressure generating elements, and means for connecting the fluid pressure to separable circuits, substantially as described.

4. In a pump, the combination with multiple cylinders, of means for connecting the said cylinders in a multiple number of separable groups with an odd number of cylinders in each group, substantially as described.

5. In a pump, the combination with multiple cylinders, of means for connecting the said cylinders in a multiple number of separable groups with a multiple number of cylinders in each group, substantially as described.

6. In a pump, the combination with multiple radial cylinders, of means for connecting the said cylinders in two separable groups, with an odd number of cylinders in each group, substantially as described.

7. In a pump the combination with an

- even number of radial cylinders, of means for connecting the alternate cylinders in one group and the intervening cylinders in a second group separable from the first group, substantially as described.
- 5 8. In a pump, the combination with multiple fluid pressure generating elements, of means operated by power for varying the volume of fluid pressure generated per cycle of operation of the said pressure generating elements, and means for connecting the fluid pressure to separable circuits, substantially as described.
- 10 9. In a pump, the combination with multiple fluid pressure generating elements, of means operated by power under manual control for varying the volume of fluid pressure generated per cycle of operation of the said pressure generating elements, and means for connecting the fluid pressure to separable circuits, substantially as described.
- 15 10. In a pump, the combination with multiple cylinders grouped into multiple sets to supply fluid pressure to separate multiple circuits, of means embodying a single crank pin coöperating with the said multiple cylinders to generate fluid pressure therein, and means for interconnecting and disconnecting the said multiple circuits, substantially as described.
- 20 11. In a fluid pressure pump, the combination with multiple cylinders, of multiple pistons coöperating therewith, means embodying a single actuating element for producing reciprocatory motion of the pistons with respect to the cylinders, and means for connecting the said cylinders to separable multiple fluid circuits, substantially as described.
- 25 12. In a fluid pressure pump, the combination with multiple cylinders, of multiple pistons coöperating therewith, an actuating element for producing reciprocatory motion of the pistons with respect to the cylinders, means for varying the extent of the reciprocations of said pistons, and means for connecting the said cylinders to separable fluid circuits, substantially as described.
- 30 13. In a fluid pressure pump, the combination with multiple cylinders, of multiple pistons coöperating therewith, an actuating element for reciprocating the pistons in the cylinders, means operated by power for varying the extent of the reciprocations of said pistons, and means for connecting the fluid pressure from the said cylinders to separable multiple circuits, substantially as described.
- 35 14. In a pump, the combination with multiple fluid pressure generating elements, of multiple fluid pressure circuits, valve mechanism coöperating therewith to cause the fluid pressure generated by certain of said generating elements to be delivered to one of said fluid pressure circuits and that generated by certain other of said generating
- elements to another of said fluid pressure circuits separable from the first fluid pressure circuit, substantially as described.
- 40 15. In a fluid pressure pump, the combination with multiple cylinders, of manifolds connecting the said cylinders into separable multiple groups, and means for interconnecting certain of said groups, substantially as described.
- 45 16. In a fluid pressure pump, the combination with multiple cylinders, of means for varying the capacity of the said cylinders, and means for connecting the said cylinders into separable multiple groups, substantially as described.
- 50 17. In a fluid pressure pump, the combination with multiple cylinders, of means for varying the capacity of the said cylinders, means for connecting the said cylinders into separable multiple groups, and means for interconnecting and disconnecting the said groups, substantially as described.
- 55 18. In a pump, the combination with fluid pressure generating elements, of means for varying the volumetric capacity per cycle of operation of the said generating elements, means actuated by power for operating the said capacity varying means, and means for storing power for operating the said capacity varying means, substantially as described.
- 60 19. In a pump, the combination with means operated by power for varying its volumetric capacity per cycle of operation, means for storing power for operating the said capacity varying means, and a secondary pump for also furnishing power for operating the said capacity varying means, substantially as described.
- 65 20. In a variable capacity pump having separable multiple fluid pressure circuits, the combination with power operated means for varying the capacity of the said pump, of means for automatically storing power from whichever circuit has the highest fluid pressure for operating the capacity varying means, substantially as described.
- 70 21. In a multiple circuit fluid pressure pump, the combination of means for collecting fluid leakage from the said multiple circuits, and means common to said multiple circuits for returning the said leakage to the said multiple circuits, substantially as described.
- 75 22. In a pump comprising means for circulating fluid through separable multiple circuits, the combination of means for collecting fluid leakage from the said circuits, and means common to said multiple circuits for automatically returning the said leakage to the said circuits, substantially as described.
- 80 23. In a pump comprising means for circulating fluid through separable multiple circuits, the combination with means for

collecting fluid leakage from the said circuits, of a single secondary pump for returning the said leakage to the said circuits, substantially as described.

5 24. In a pump comprising multiple fluid pressure generating elements the combination with means for connecting the fluid pressure from certain of the said generating elements to a fluid circuit separable from 10 that to which the fluid pressure from certain other of the said generating elements is connected, of means for collecting fluid leakage from the several fluid circuits and means for returning the said leakage to the said fluid 15 circuits in proportion to the leakage therefrom, substantially as described.

25. In a multiple circuit pump the circuits of which are separable from each other, the combination with means for collecting 20 leakage from the said multiple circuits, of means for returning the said leakage so collected to each of the said multiple circuits in proportion to the amount leaking therefrom, substantially as described.

25. 26. In a multiple circuit pump, the circuits of which are separable from each other, the combination with means for collecting leakage from the said multiple circuits, of a secondary pump for automatically pumping 30 back to each of the said multiple circuits the said leakage so collected in proportion to the amount leaking therefrom, substantially as described.

27. In a fluid pressure pump, the combination with cylinders, coöperating pistons and a main driving shaft, of means for varying the length of stroke of said pistons, an adjusting casing arranged around said driving shaft, stationary adjusting cylinders arranged in said casing, a secondary fluid pressure pump in said casing driven by said driving shaft, and means for utilizing fluid pressure from said secondary pump in said adjusting cylinders for operating the 45 said stroke varying means, substantially as described.

28. In a pump, the combination with means embodying a crank shaft for varying its stroke, of a sleeve having a screw 50 thread detachably secured to the said crank shaft, a nut slidably mounted on said thread, a sleeve coacting with said nut and the said stroke varying means, a yoke journaled on said nut, and means for moving said yoke 55 to vary the said stroke, substantially as described.

29. In a pump, the combination with means embodying a crank shaft for varying its stroke, of a sleeve having a screw detachably secured to the said crank shaft, a nut slidably mounted on said thread, a sleeve coacting with said nut and the said stroke varying means, a yoke journaled on said nut, and power operated means for moving

said yoke to vary the said stroke, substantially as described. 65

30. In a pump, the combination with means for varying its stroke embodying a crank shaft with a crank pin formed thereon and a bushing eccentrically mounted on said crank pin, of a sleeve having a screw thread detachably secured to said crank shaft, a nut slidably mounted on said thread, a sleeve surrounding said nut which is slidably connected thereto, means connecting the said sleeve to the said bushing, and means for sliding the said nut with reference to said sleeve and said thread to rotate the said bushing on the said crank pin to vary the said stroke, substantially as described. 70 75 80

31. In a pump comprising cylinders with coöperating pistons, the combination with a crank shaft for operating said pistons, means for varying the length of stroke of said pistons, of a casing surrounding said stroke varying means and carrying a cylinder with a coöperating fluid pressure operated piston connected to said stroke varying means, a fluid pressure supply for forcing said piston to operate the said stroke varying means, and 90 means interconnecting the said stroke varying means and the said casing whereby the reaction from the force moving the said piston will come on the said casing, substantially as described. 95

32. In a fluid pressure pump embodying a cylinder with a piston reciprocatably mounted therein, the combination with an element to which the said piston is connected and by which it is reciprocated, of a 100 port through which the fluid flows to and from the said cylinder, an outlet passage through which the fluid flows after passing said port, a valve coöperating with said port and embodying means for causing the caliber of the outlet for flow of the fluid through the said port to be increased in synchronism with the accelerations of the said piston in its reciprocations, and means for producing positive relative motion between the said valve and said port, said valve being adapted to cause the fluid before being released to flow out of said cylinder through said port to be raised in pressure, substantially as described. 105 110 115

33. In a fluid pump embodying a cylinder with a piston reciprocatably mounted therein, the combination with an element to which the said piston is connected and by which it is reciprocated, of a port through 120 which the fluid flows to and from the said cylinder, a valve coöperating with said port to open and close the same in synchronism with the reciprocations of said piston and means for causing the caliber of the outlet 125 for flow of the fluid through the said port to be increased and retarded in synchronism with the accelerations and retardations of

the piston in its reciprocations, substantially as described.

34. In a fluid pump embodying a cylinder with a piston reciprocatably mounted therein, the combination with an element to which the said piston is connected and by which it is reciprocated, of a port through which the fluid flows to and from the said cylinder, and a valve coöperating with said port and embodying means for causing the caliber of the outlet for flow of the fluid through the said port to be increased in synchronism with the accelerations of the said piston in its reciprocations, substantially as described.

35. In a fluid pressure pump embodying a cylinder with a piston reciprocatably mounted therein, the combination with an element to which the said piston is connected and by which it is reciprocated, of a port through which the fluid flows to and from the said cylinder, an outlet passage through which the fluid flows after passing said port, a valve coöperating with said port, and means for producing positive relative motion between the said valve and the said port, said valve being adapted to cause the fluid before being released to flow out of said cylinder through said port to be raised in pressure to substantially equal the pressure in the said outlet passage, substantially as described.

36. In a pump, the combination with a cylinder, a piston, a rotating driving shaft and means for causing a uniform rate of rotation of said driving shaft to reciprocate said piston in said cylinder at a variable rate per rotation of the said shaft and thereby cause fluid to be forced from and drawn into said cylinder at a variable rate, a valve chamber connected to said cylinder by a passage through which fluid flows to and from said cylinder, a port in said valve chamber through which said fluid flows, a reciprocating valve opening and closing said port, and means for causing the said valve to vary the area of port opening at substantially the same rate per cycle of motion of the piston as the velocity of travel of the piston varies in the same cycle, substantially as described.

37. In a pump or motor embodying cylinders with reciprocating pistons and a crank shaft, the combination of reciprocating piston valves, a rotating crank 90 degrees distant angularly from the crank of said shaft for operating said valves, heads on said valves having a series of V notches forming serrations in the edges thereof, and valve ports the area of opening of which is so controlled by said valve heads that the area varies substantially in synchronism with the reciprocations of the said pistons in said cylinders, substantially as described.

38. The combination with a pump of a storage reservoir normally closed at one end, a free piston slidably mounted in said reservoir, a compressible fluid trapped between said piston and the closed end of said reservoir, means for replenishing or increasing the compressible fluid, a more viscous fluid between the said piston and the said compressible fluid, and means for admitting fluid pressure from the said pump into the opposite end of said reservoir to compress the said compressible fluid, substantially as described.

39. In a variable stroke fluid pressure pump, the combination with power operated mechanism for adjusting the stroke of a control element, of means coacting with said control element to increase the resistance to movement of said element when the stroke is zero, substantially as described.

40. In a variable stroke fluid pressure pump, the combination with mechanism for adjusting the stroke on both sides of zero, of a control element and means coacting therewith for increasing the resistance to movement of said control element when it has been moved to one position corresponding with zero stroke obtained by adjusting the stroke from one side of zero to zero and for increasing the resistance to movement when the said control element has been moved to another position corresponding with zero stroke obtained by adjusting the stroke from the other side of zero to zero, substantially as described.

41. In a variable stroke fluid pressure pump, the combination with mechanism for adjusting the stroke, of a control element means coacting with said control element to increase the resistance to movement of said element when the stroke is zero and means for adjusting the position of said coacting means, substantially as described.

42. In a variable stroke fluid pressure pump, the combination with mechanism for adjusting the stroke, of a control element, means coacting with said control element to increase the resistance to movement of said element when the stroke is zero and means for adjusting the resistance of said coacting means, substantially as described.

43. In a variable stroke fluid pressure pump, the combination of fluid pressure operated mechanism for adjusting the stroke, means comprising a floating lever for controlling the fluid pressure adjusting means, and means coacting with said floating lever to enable the said stroke to be adjusted by manual power exerted through said floating lever.

44. In a mechanism of the class described the combination of multiple fluid pressure generating elements, separate circuits for said elements, and means for simultaneously

- varying the volumetric capacity of said elements.
45. In a mechanism of the class described the combination of multiple fluid pressure generating elements, separate circuits for said elements, and means for simultaneously and equally varying the volumetric capacity of said elements.
46. In a mechanism of the class described, the combination of multiple fluid pressure generating elements, separate circuits for said elements, means for simultaneously varying the volumetric capacity of said elements, and means for inter-connecting and disconnecting said circuits.
47. In a mechanism of the class described, the combination of multiple fluid pressure generating elements, separate circuits for said elements, means for simultaneously and equally varying the volumetric capacity of said elements, and means for interconnecting and disconnecting said circuits.
48. In a mechanism of the class described, the combination of multiple fluid pressure generating elements having separate circuits, separate fluid pressure operated motors in said circuits, and means for simultaneously and equally varying the speeds of said motors.
49. In a mechanism of the class described, the combination of multiple fluid pressure generating elements having separate circuits, separate fluid pressure operated motors in said circuits, and means for simultaneously and inversely varying the speeds of said motors.
50. In a mechanism of the class described, the combination of a pump having multiple cylinders and reciprocating pistons, a single actuating member for all said pistons, passages interconnecting said cylinders in separate groups, separate fluid pressure operated motors in circuit with said separate groups, and means for adjusting said actuating member to simultaneously and equally vary the capacity of all said cylinders.
51. In a pump, the combination of multiple fluid pressure generating elements, separate circuits receiving the fluid under pressure from said elements and means for interconnecting and disconnecting the circuits, the said means being adjustable to permit all or any desired portion of the fluid from certain of said generating elements to pass into the circuit of another of said elements.
52. In a pump, the combination of multiple fluid pressure generating elements, intake and delivery passages for each of said elements, means for interconnecting and disconnecting said intake passages, means for interconnecting and disconnecting said delivery passages, and means for operating said interconnecting and disconnecting means in synchronism.
53. In a pump, the combination of multiple fluid pressure generating elements, intake and delivery passages for each of said elements, means for interconnecting and disconnecting said intake passages and for interconnecting and disconnecting said delivery passages and means for operating said interconnecting and disconnecting means to permit all or any desired portion of the fluid in the passages of certain of said elements to pass into the corresponding passages of other of said elements.
54. In a pump, the combination of multiple cylinders, connected in separate groups, a separate circuit for each group, means for interconnecting and disconnecting the high pressure sides of said circuits, and means operable in synchronism therewith for interconnecting and disconnecting the low pressure sides of said circuits.
55. In a pump, the combination of multiple cylinders connected in separate groups, a separate circuit for each group, means for interconnecting and disconnecting said circuits comprising a valve chamber for each circuit provided with intake and delivery ports for the high pressure side of its circuit and for the low pressure side of its circuit, and with ports interconnecting the chambers, valve bodies movable in said chambers and forming separate passages for the high pressure and low pressure sides of said circuits and provided with lobes adapted to coöperate with certain of the ports of the chambers.
56. In a pump, the combination of multiple fluid pressure generating elements, delivery passages for each of said elements, means for interconnecting and disconnecting said passages comprising a valve chamber for each passage having intake and delivery ports, ports connecting said chambers, a valve body movable in each chamber and provided with lobes coöperating with the interconnecting ports and the delivery ports of said chambers.
57. In a pump, the combination of multiple cylinders connected in separate groups, a separate circuit for each group, means for interconnecting and disconnecting said circuits comprising a valve chamber for each circuit provided with intake and delivery ports for the high pressure side of its circuit and for the low pressure side of its circuit, and with ports interconnecting the chambers, valve bodies movable in said chambers and forming separate passages for the high pressure and low pressure sides of said circuits and provided with lobes adapted to coöperate with certain of the ports of the chambers, and means for operating said valve bodies in synchronism.
58. In a pump, the combination of multiple fluid pressure generating elements, de-

- livery passages for each of said elements, means for interconnecting and disconnecting said passages comprising a valve chamber for each passage having intake and delivery ports, ports connecting said chambers, a valve body movable in each chamber and provided with lobes coöperating with the interconnecting ports and the delivery ports of said chambers, and means for operating said valve bodies in synchronism.
59. In a pump the combination of multiple fluid pressure generating elements,

separate intake passages for each of said elements, means for interconnecting and disconnecting said passages comprising a valve chamber for each passage having intake and delivery ports, a valve body movable in each chamber and provided with lobes coöperating with the interconnecting ports and the intake ports of said chambers. 15
